(57) **CLAIM**

The ornamental design for a watch, as shown and described.

DESCRIPTION

FIG. 1 is a front perspective view of a watch, showing my new design;

FIG. 2 is a rear perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a front perspective view of the watch in a first usage environment; and,

FIG. 9 is a front perspective view of the watch in a second usage environment.

The dashed broken lines show portions of the watch that form no part of the claimed design. The dashed broken lines showing a band in FIGS. 8-9 are for the purpose of illustrating environment and form no part of the claimed design.

1 Claim, 8 Drawing Sheets
